UNITED STATES PATENT OFFICE.

RUDOLF GETZLAFF, OF AMSTERDAM, GEORGIA.

PNEUMATIC COTTON-PICKER.

SPECIFICATION forming part of Letters Patent No. 763,389, dated June 28, 1904.

Application filed April 13, 1904. Serial No. 203,008. (No model.)

To all whom it may concern:

Be it known that I, RUDOLF GETZLAFF, a citizen of the United States, residing at Amsterdam, in the county of Decatur and State 5 of Georgia, have invented a new and useful Pneumatic Cotton-Picker, of which the following is a specification.

This invention relates to cotton-picking devices in which a current of air is set up in a tube by means of a suitably-arranged fan or blower, the same discharging into a receptacle, the suction thus produced serving to remove from the plants the open bolls which are ready for picking and to convey the same 10 through the tubular conduit and through the blower mechanism into the receptacle provided therefor.

The present invention has for its object to provide a device of this class which shall possess 20 superior advantages in point of simplicity and durability and which shall be thoroughly feasible, practical, and efficient in operation.

With these and other ends in view, which 25 will readily appear as the nature of the invention is better understood, the same consists in the improved construction and novel arrangement and combination of parts, which will be hereinafter fully described, and particularly pointed out in the claims.

In the accompanying drawings has been illustrated a simple and preferred form of embodiment of the invention, it being, however, understood that I do not necessarily limit 35 myself to the precise structural details therein exhibited, but reserve the right to all changes, alterations, and modifications which come fairly within the scope of the invention and which may be resorted to without departing 40 from the spirit or sacrificing the advantages of the same.

In said drawings, Figure 1 is a side elevation of a cotton-picking machine constructed in accordance with the principles of the invention. Fig. 2 is a top plan view, partly in section, of the same.

Corresponding parts in both figures are indicated by similar numerals of reference.

In the form of embodiment of the invention 50 herein illustrated is included a platform 1, sup-

ported upon wheels 2 and 3, the former being the front wheels and the latter the hind wheels. A spring 4 and a bolster 5 may, if desired, be interposed between the front wheels and the front end of the platform. The platform 55 supports at its front end a seat 6 and at its rear end a seat 7. Suitably supported intermediately upon the platform is a light but capacious receptacle 8, with which is connected the discharge-tube 9 of a fan-casing 10, which 60 is likewise suitably supported upon the platform. The fan-casing is provided on opposite sides thereof with air-intakes connected with the branches of a bifurcated pipe 11, which is connected by means of a suitable 65 joint with a flexible pipe or tube 12. The branches of the bifurcated pipe 11 have bearings for the fan-shaft 13, which carries within the casing 10 a fan 14 of ordinary construction. The bearings for the fan-shaft are preferably in the nature of tubes 15, extending 70 through the branches of the bifurcated pipe in the direction of the hub of the fan and practically contacting therewith, so as to prevent possibility of cotton becoming wrapped 75 upon the fan-shaft when the latter is in operation, and thus interfering with its free rotation.

The fan may be driven by any suitable means; but in the drawings has been illustrated a sprocket-wheel 16 upon one end of the fan-shaft, said sprocket-wheel being connected by a chain 17 with a sprocket-wheel 18 upon one of the transporting-wheels 3 of the machine.

The flexible tube 12 carries at the extremity thereof a funnel 19, which constitutes the inlet. I prefer to provide said funnel with a hood or flange 20 at the lower edge thereof, in order that it may more efficiently engage 90 the plants that are to be operated upon, as will be presently described. The funnel 19 is constructed of sheet metal, and suitably connected therewith, as by means of rivets 21, is an upwardly-extending rod 22, provided at its upper end with handles 23, which are preferably bent in the semblance of a bicycle handle-bar. These handles, it will be observed, can be conveniently grasped by an operator seated upon the rearwardly-facing 100

seat 7, who by means of said handle and rod will be enabled to perfectly control the movement of the intake-funnel at the end of the flexible tube 12. Foot-rests 24 and 25 may 5 be provided for the driver as well as for the operator seated upon the rearwardly-facing seat of the machine.

In operation the machine is driven over the field, the draft-animals walking on either side 10 of the row which is straddled by the machine, the running-gear being of sufficient height to support the platform at a height where it will not injuriously interfere with the plants. The operator occupying the seat 7 will firmly grasp 15 the handle-bars and is enabled thereby to direct the intake-funnel against the growing plants, scraping loosely over the same, as will be readily understood, the intake funnel being of an area sufficient to cover a large portion 20 of the cotton-plant. The progress of the machine will be sufficiently slow to enable the operator to so manipulate the intake-funnel that it will be brought into contact with practically every portion of each plant, and the 25 ripe cotton which is ready for picking and which is therefore easily loosened will become readily detached by the suction set up by the fan and will be conveyed through the tube 12 and through the fan-casing and the discharge- 30 pipe of the latter into the receptacle 8.

Having thus described the invention, what is claimed is—

1. In a device of the class described, a wheel-

supported platform, a receptacle supported thereon, a fan-casing having a discharge-spout 35 connected with said receptacle, a flexible tube connected with air-intakes in the sides of the fan-casing, a driven fan in the latter, a funnel at the free end of the flexible tube, an upright rod connected with said funnel, a handle-bar at the upper end of said rod, and a seat supported upon the platform convenient to said handle-bar.

2. In a device of the class described, a wheel-supported platform, a forwardly-facing seat 45 at the front end of said platform, a rearwardly-facing seat at the rear end of said platform, an intermediately-supported receptacle, a fan-casing discharging into the latter, a bifurcated pipe connected with air-intakes in the sides of 50 the fan-casing, a driven fan in the latter, a flexible tube connected with said pipe, an intake-funnel at the free end of the flexible tube, an upright connected with said funnel, and a handle-bar at the upper end of said upright 55 convenient to the operator seated in the rearwardly-facing seat at the rear end of the platform.

In testimony that I claim the foregoing as my own I have hereto affixed my signature in 60 the presence of two witnesses.

RUDOLF GETZLAFF.
